UNITED STATES PATENT OFFICE.

THEODORE SNYPP, OF NEWPORT, OHIO.

LABEL-HOLDING DEVICE FOR BOTTLES.

SPECIFICATION forming part of Letters Patent No. 337,713, dated March 9, 1886.

Application filed October 16, 1884. Serial No. 145,680. (No model.)

To all whom it may concern:

Be it known that I, THEODORE SNYPP, of Newport, Wynant P. O., in the county of Shelby and State of Ohio, have invented certain new and useful Improvements in Label-Holding Devices for Bottles; and I do hereby declare that the following is a full, clear, and exact description of the invention, which will enable others skilled in the art to which it applies to make and use the same, reference being had to the accompanying drawings, and to the letters of reference marked thereon, which form part of this specification.

The object of this invention is to provide a suitable label-holding device for bottles, boxes, packages, and the like; and it consists, substantially, in the parts as constructed, and in the particular combinations to be hereinafter distinctly described, and pointed out in the claims.

The invention is designed more particularly for use in drug-stores and such like places where poisonous and dangerous drugs are kept in stock, and was devised for the purpose of preventing the heretofore too frequent accidents resulting from the errors of clerks in mistaking bottles containing poisonous material or substances for others in the preparation or compounding of prescriptions.

Referring to the annexed sheet of drawings, Figure 1 represents a bottle having a label-holder thereon constructed in accordance with my invention. Fig. 2 represents a sectional view of the holder proper to represent the interior disposition of parts, and Fig. 3 a view in detail.

The device is so constructed as to hold as many labels as may be desired, a single one at a time being readily slipped out for the purpose of pasting it on the vial or box that is to contain the purchased drug or material. The labels themselves are to have the name of the drug or material printed on them, and they are placed in the holder or device, preferably with the gummed side outward, so that they can be withdrawn one at a time by simply sliding the finger across, to which they are caused to adhere by the natural moisture thereof. The name of the drug or medicine that is contained in the bottle on which the holder is placed is to be printed or otherwise indicated on the device itself, so that it is

simply necessary for the clerk to read the inscription on the device, proper care of course being observed in the first instance in having all to correspond.

Reference being had to the several parts by letter, A represents a bottle, and B the label-holder proper.

To provide means for attaching the device to bottles already in hand, I furnish to each side thereof small rings or loops a, in one of which I secure one end of a metallic strap or ribbon, C, while in the opposite one the free end of the strap is adjustable, so as to enable the device to be fitted to bottles of varying circumferences. It will thus be seen that the device and bottles may be sold together, the device being attachable to bottles of the ordinary construction.

The construction of the holder B is substantially as follows: c represents a small metallic box or casing having a concave back, c', conforming in shape to the contour of the ordinary cylindric bottles, although for square bottles this back c' may be flat. The front consists of a plate having a portion cut or slotted out, as at d, by which the labels i are exposed to permit the finger to be placed thereon in slipping them out. Within the holder are arranged two plates or strips, e e', the former being preferably stationary, while the latter is movable. Between these plates are arranged coiled springs g g, and before the plate e', between it and the outer front plate, the labels are placed. The tendency of the springs is to force the labels outward, and as fast as they are removed the plate e' is forced outward.

Instead of coiled springs, I may use springs of any other form—as, for instance, an elliptic spring; but for all general purposes I have found the construction herein shown to answer all requirements. The back of the box is open and the top and bottom plates curved or otherwise shaped to fit the face of the vessel to which it is to be attached.

When attached, the face of the vessel forms the rear wall of the box and furnishes a stop for the rear plate, e, of the spring-follower.

When it is desired to place a stock of labels within the box, the box should be detached and the plates e e' and the springs g g removed. The labels may then be placed within the box

against the front plate, and after replacing the plates *e e'* and the springs *g* the box will be ready for attachment. The strap *C* is bent to form a serpentine-spring portion, *j*, (shown 5 in Fig. 3,) at or near the center of the strap *C*, thus causing it to fit closely to the object which the strap encircles. In addition to this, the strap is adapted to fit various-sized bodies in the following manner, to wit: The strap is 10 made not only long enough to reach from one of the loops in the label-holder around the object to which the label-holder is to be secured and then just reach the loop in the opposite side of the label-holder, but it extends beyond 15 said loop, and when it has been drawn through said loop far enough to make the strap as taut as is desired it may be bent at any desired point, and by passing it through the loop from the outside the free end, or that portion of the 20 strap between the end and the point where it is bent in the loop, is simply tucked under the strap *C* out of the way, as will be clearly seen by reference to Fig. 3.

By my invention the labels of a particular 25 kind may all be kept together, and thus prevented from being scattered about with others indiscriminately.

Heretofore the custom has been to keep the labels in drawers provided with separate compartments or divisions by which they are di- 30

vided; but in such practice the labels frequently warp or curl up and spring from their own places over into some other of the adjacent compartments, frequently causing mishaps. By my invention these difficulties are entirely 35 obviated.

Having thus described my invention, what I claim is—

1. A label-holder consisting of the casing adapted to hold labels, and provided with 40 loops *a*, in combination with a strap adapted to be secured in said loops, and bent near its center to form a serpentine spring, substantially as set forth.

2. A label-holder consisting of a casing 45 adapted to hold labels, and provided with loops *a*, in combination with a strap which is bent to form a spring portion near the center of the same, and adjustable independently of the spring portion to fit and encircle bodies of 50 different circumferences, substantially as set forth.

In testimony that I claim the foregoing as my own I affix my signature in presence of two witnesses.

THEODORE SNYPP.
